US0D1072169S

(12) **United States Design Patent** (10) **Patent No.:** **US D1,072,169 S**
(45) **Date of Patent:** **** Apr. 22, 2025**

(54) **WATER TREATMENT APPARATUS**

(71) Applicant: **KYUNGDONG NAVIEN CO., LTD.**,
Pyeongtaek-si (KR)

(72) Inventor: **Hye Jin Park**, Seoul (KR)

(73) Assignee: **KYUNGDONG NAVIEN CO., LTD.**,
Pyeongtaek-si (KR)

(**) Term: **15 Years**

(21) Appl. No.: **29/886,467**

(22) Filed: **Mar. 8, 2023**

(30) **Foreign Application Priority Data**

Dec. 5, 2022 (KR) 30-2022-0051071

(51) **LOC (15) Cl.** **23-01**

(57) **CLAIM**

The ornamental design for a water treatment apparatus as
shown and described.

DESCRIPTION

FIG. 1 is a perspective view of a water treatment apparatus,
showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

1 Claim, 7 Drawing Sheets
